ABSTRACT: In a color television tube of the type including a striped tricolor luminescent screen and a postfocusing grid adjacent the screen, the grid is set at a potential higher than that which ensures focusing on the screen of the electron beam or beams impinging on the grid. Diaphragm means is provided to prevent lateral portions of the cross section of the beam or beams from impinging upon the screen. Secondary electron emissions are reduced or substantially eliminated because the electric field between screen and grid is reduced. As a result, the contrast provided by the tube is increased.

COLOR TELEVISION TUBE

REFERENCE TO RELATED APPLICATION

This is a continuation-in-part of my copending application Ser. No. 574,370, filed Aug. 23, 1966 and now abandoned.

The present invention relates to an improvement in color television tubes with a screen formed by phosphor strips, comprising, in the immediate neighborhood of the screen and facing it, a grid of fine wires held at a potential lower than that of the screen and forming therewith a system of cylindrical lenses for each electron beam, or the single electron beam.

It is known that tubes of this kind present a clear advantage over tubes whose screen is preceded by a shadow mask, that is to say, in the case of a screen formed by phosphor strips, by a wall having only narrow apertures parallel to the phosphor strips, wherein the total surface of the apertures presents only a very small part of the total surface of the mask.

A grid tube has a higher optical efficiency and, therefore, may reach a much greater brightness, since the majority of the electrons reaches the screen while the greater part of electrons is stopped by the mask in a shadow mask tube.

However, the tubes with wire grids of known types have poor contrast, due to the secondary emission of the grid and the screen.

The present invention eliminates or at least considerably reduces this drawback by reducing the electric field in the space comprised between the screen and the grid.

The present invention is applied to color television tubes of the type comprising a screen formed by phosphor strips of different colors, and a grid facing the screen and adjacent thereto. The grid defines apertures at least approximately parallel to the strips, and means is provided for producing one or more electron beams directed toward the screen. A high positive potential V_E is applied to the screen and a potential V_g lower than V_E is applied to the grid whereby the grid-screen assembly defines a system of cylindrical lenses convergent for the beam or beams. According to this invention, the ratio of potential V_g to potential V_E is greater than that which focuses the electron beam or beams on the screen, being greater than one-quarter of the potential V_E , preferably between one-third and three-quarters of the potential V_E . A diaphragm means is preferably arranged to prevent lateral portions of the cross section of the electron beam from impinging upon the strips.

The above and other objects, advantages and features of the invention will become more apparent from the following detailed description of certain preferred embodiments, taken in conjunction with the accompanying drawing wherein:

FIG. 1 diagrammatically shows a cross section of part of a known tube to which the invention may be applied;

FIG. 2 shows the configuration of equipotential lines between the screen and the grid of the tube of FIG. 1, and the trajectories of the rays of an electron beam in the space between the grid and screen;

FIG. 3 illustrates the secondary emission phenomena in the space between grid and screen;

FIG. 4 shows the purity defect which may be caused by an imperfect focusing of the spot on the screen in the absence of a correction by a complex diaphragm, limiting the width of the spot;

FIGS. 5 and 6 show an embodiment of the invention, using a complex diaphragm acting at the level of the grid;

FIG. 7 shows a preferred embodiment of the complex diaphragm of FIGS. 5 and 6;

FIGS. 8, 9, and 10 show three embodiments of the invention, using complex diaphragms combined with the grid; and

FIG. 11 shows another embodiment of the invention, in which the complex diaphragm is combined with the screen.

In all figures, the same reference letters or numerals designate identical parts or elements. For the sake of clarity, the ratios between dimensions are not drawn to scale.

The invention will be described, by way of example only, with reference to a tube with a screen with vertical phosphor strips and with three guns, the screen having a regular structure, i.e., formed by strips which are exactly parallel and of equal widths.

FIG. 1 shows diagrammatically in horizontal cross section the left part of a tube of this kind.

Inside the envelope 1 are shown:

10 The screen E formed by vertical phosphor strips, successively green, red and blue, three consecutive strips forming a triplet. The width of these strips, being about one-third of a millimeter, is shown greatly enlarged relative to the dimensions of the envelope.

15 In front of the screen is a grid g of fine wires, parallel to the strips and delimiting the triplets, as seen from a point lying on the axis of the tube, the spacing of the grid wires being constant and smaller than the width of a triplet. The distance between grid and screen may be of the order of 2 cm. and is also exaggerated in the drawing.

20 Only one of the three guns, i.e. the "red gun", "blue gun" and "green gun", associated, respectively, with the phosphor strips of the three colors, is shown here, the gun being the center gun 3, in this case the red gun.

25 One of the elements 2 of the magnetic deflection unit is also shown.

30 Not shown are the conductive coating, often called the "anode", covering the envelope internally between a vertical plane preceding the output of the guns and a vertical plane near the grid; the purity correction electrode, preferably used in these tubes; and the convergence device.

35 A conventional mode of operation of this tube will now be briefly outlined.

35 The cathodes of the guns are approximately at ground potential.

40 The screen E is at a very high potential, of the order of 20,000 volts or even more, while the grid g carries a much lower potential, for example 5,000 V. The above-mentioned anode and the electrodes of the three guns having the highest voltage are at voltages equal to that of the grid or at least of the same order.

45 The magnetic deflection unit sweeps the three beams coming from the guns and intensity modulated by the "red", "blue" and "green" signals, over the screen, line by line, as in the case of monochrome tubes.

50 The "deflection centers" of the red, green and blue beams, located in the same vertical plane, the so-called "deflection plane", are shown in FIG. 1 by the straight line x-x'. The center of deflection of the red beam is indicated at 4, the beam 50 itself being shown by a dotted line in one of its positions.

The grid-screen arrangement constitutes a system of cylindrical lenses for the beams, which assures the focusing in the screen plane, i.e. the luminescent surface.

55 For a satisfactory picture, two conditions must be fulfilled, namely those of purity and of convergence. The first requires that each beam should at all times be focused on a strip of the associated color, the second that the three spots are not far from each other, i.e. correspond to the same point of the picture.

60 FIG. 2 shows on a very large scale the center portion of the screen with the red, blue and green vertical strips R, G and B. These strips are covered with a very thin conducting layer or coating 5, whereby the screen potential can be applied to them, but sufficiently thin to allow the electrons impinging on it to reach the phosphors forming the strips.

65 The drawing shows in broken lines the equipotential lines between screen and grid, and the beam 9 coming from the red gun, represented by a number of electron trajectories drawn in solid lines. These electron trajectories are substantially parallel and their common direction is normal to the grid immediately in front of the space between grid and screen. This perpendicular incidence follows from the fact that the center portion of the screen has been shown, but the parallelism of the trajectories is an approximation which is valid for the

whose surface of the screen, taking into account the magnitudes involved. In fact, the focusing produced by the electron optical system of the gun reduces the diameter of the beam, which does not exceed about 3-4 mm. at the outlet of the gun, to about 1 mm. immediately in front of the grid. The distance between the output of the gun and the grid is, for example, some 30-40 cm., and the trajectories may, therefore, be regarded as substantially parallel for any sweep angle.

The grid-screen arrangement, with regard to the potential distribution in the space between grid and screen, forms an assembly of convergent cylindrical lenses (one lens corresponding to each grid interval) which are substantially identical and have the same focal plane which coincides, as is known, substantially with the surface of the screen.

Each lens sequentially receives the beams coming from each of the three guns in the form of a beam of rays which are substantially parallel and focuses them at one point of its focal plane. If the condition of purity is observed, this focusing takes place for each beam on a phosphor strip of the associated color.

The focusing of the beams in the plane of the screen requires, in practice, for a grid-screen spacing of the order of 2 cm., a ratio $r = V_g/V_E$ equal approximately to 1/4, where V_E is the screen potential and V_g the grid potential.

This gives $V_E - V_g = V_E - r \cdot V_E = V_E (1 - r)$, with $(1 - r)$ of the order of 3/4.

It is necessary for V_E to be high, e.g., of the order of 20,000 v. to assure the adequate excitation of the phosphors.

It follows from the preceding that, in known tubes of this type, the potential difference $V_E - V_g$ is considerable, equal to 15,000 v., with $V_E = 20,000$ v. and $r = 1/4$, which is, as will be shown, a serious drawback as far as the secondary emission of the grid is concerned.

The quality of a tube with regard to contrast can be defined by the ratio $C = L_M/L_m$, where L_M and L_m are respectively the maximum and minimum brightnesses obtainable simultaneously on the screen with white light (by means of applying appropriate voltages to the three guns), with a specific test pattern generator.

A high value of C is desirable, but grid secondary emission phenomena prevent reaching the desired values in grid tubes of the known type.

It is impossible to suppress secondary emission by changing the nature of the conducting wires of the grid, as all conducting substances give rise to at least some secondary emission, and various reasons limit the choice of materials used.

It should be noted that the impact of incident beams gives rise to secondary emission not only from the grid but also from the screen. However, the former is much more critical as to its optical consequences, as will be explained hereinafter.

FIG. 3 illustrates the phenomenon of secondary emission in the space between grid and screen.

This drawing shows on a smaller scale the center portion of the screen E, the corresponding part of the grid g, and the red beam 9.

The solid arrows 7 illustrate the initial parts of the trajectories of secondary electrons emitted by the coating 5 due to the impact of electrons of the incident beam. Secondary electrons, reflected by the grid, fall back onto different portions of the screen.

On the other hand, the incident beam liberates from the grid secondary electrons, many of which will reach the screen following trajectories practically perpendicular to it, such as illustrated by dotted lines 8.

In accordance with the invention, an important reduction of unwanted secondary electron emissions is obtained by using a ratio $r = V_g/V_E$ greater than the value $r = 1/4$, which ensures the focusing of the beam beyond the surface or plane of the screen.

However, the ratio r should not become too high and must remain smaller than 3/4. Otherwise, the focusing of the beam in the space between grid and screen becomes too weak for a correct operation of the tube. The preferred ratio is between 1/3 and 3/4.

Experience shows that it is possible to start, for instance, with a screen voltage V_E of the order of 20,000 volts or more and a ratio r of the order of 0.3 to 0.35, and to adjust the barrier effect of the conductive coating so that a proper excitation of the screen by primary electron beams is obtained without any perceptible image of the grid and with a defocusing sufficiently moderate so as not to involve any noticeable purity defect with a tube having phosphor strips of the order of 0.3 millimeters wide, it being understood that the electron optical devices of the tube are matched to these conditions of operation.

Using a ratio r much greater than 1/4, for instance $r = 1/2$, can, for a given strip width, lead to the undesired result that the diameter of the spot on the screen becomes greater than the width of the strips. But this defect can be corrected by means of a diaphragm in accordance with the invention.

One can use an independent complex diaphragm 10, as shown in FIG. 5, which shows the center portion of the screen E and the grid g, and the beam 9 whose shaded lateral parts 90 are stopped by the complex diaphragm. The diaphragm may be, for example, spaced 1 cm. from the grid and have the same potential as the latter.

The complex diaphragm consists of vertical strips 11 which are impermeable to electrons, separated by slots parallel to the strips so as to stop parts 90 of the beam 9 which, after focusing or rather partial focusing by the grid-screen system, would produce lateral portions of the spot overlapping the red strip.

The strips 11 are so arranged as to limit the beam in this manner at any angle of sweep, as shown in FIG. 6, which corresponds to FIG. 5 but shows another portion of the screen, where the incidence of the beam is no longer perpendicular to the grid. The dotted lines show the final diameter of the beam if the diaphragm were not present.

Generally, if the complex diaphragm restores the purity for the beam of the center gun, it will act satisfactorily for the other two beams too. However, the width of the strips may be slightly adjusted in order to avoid any insufficiency.

It should be noted that, if the diaphragm 10 and the grid g are at the same potential V_g , the diaphragm is in fact the real grid, and particularly that it is the diaphragm that gives rise to an image on the screen if the coating and the potentials used are not according to the invention.

Consequently, the grid may be eliminated. However, it can be retained as an auxiliary element while being preferably brought to a voltage V' , slightly lower than the voltage V_g applied to the diaphragm. It is easily seen that this arrangement is advantageous as far as the effects of secondary emission are concerned.

Whether the grid g is retained or not, it should be noted that, since the beam incident on the diaphragm-grid 10 has a substantially circular cross section, the reduction in percentage of the surface of the beam cross section, due to the action of the diaphragm, is much less than the reduction in percentage of the width of the beam.

Moreover, since the density of the beam is greater in its center than at its periphery (the distribution of the electrons is substantially Gaussian along a diameter of the beam with its maximum on the axis), the percent drop in the number of electrons reaching the screen is even smaller.

FIG. 7 illustrates in plan view and cross section a preferred embodiment of the diaphragm-grid 10. It is formed by a lattice 10 of very fine wires, wherein the strips 11 of the diaphragm are formed by depositing a suitable substance, such as carbon, silver or aluminum, for instance by photographic methods.

FIGS. 8, 9, and 10 show three further embodiments of the diaphragm.

FIG. 8 the cross section of the grid wires is so enlarged that the wires stop the undesirable portion of the beam.

This, however, is not an optimum solution, as it involves the risk of haloes appearing around the spots.

In the embodiment of FIG. 9, the effect of a diaphragm is produced in each grid interval by bounding this interval not by a single wire but by an assembly of three wires with coplanar

axes and tangential cross sections. The diameters of the two lateral wires are preferably smaller than that of the center wire, thus imparting excellent antivibration properties to the grid, since the respective resonant frequencies of the two outer wires and of the center wire are different. For example, the diameters may have a ratio of 7/8 although a higher ratio is shown in the drawing. All three wires may have different diameters.

The diaphragm of FIG. 10 also uses three wires in a group, the wires having unequal diameters but their axes forming the edges of a triangular prism. The manufacturing of this arrangement is easier than that of the complex diaphragm of FIG. 9.

Finally, FIG. 11 shows an embodiment of the invention, in which the diaphragm does not limit the width of the beam but only the width of the active portion of the beam.

Each luminescent strip of triplets is reduced in width and surrounded by two "dead" strips 23 for which the screen support is not covered with phosphors and may be covered advantageously with carbon, for example. The width of the dead strips is such that they cover the portions of the screen which the lateral portions of two beams overlap, and are superimposed so that the active portions of the three beams cannot overlap, and each beam excites only the color band associated with it.

In FIG. 11 the width of the dead strips is more than the strict minimum (for which in the drawing the red beam would cover on the screen the red center strip R and the two adjacent dead strips), which facilitates the achievement of purity while allowing for larger manufacturing and/or adjustment tolerances. Naturally, reducing the width of the dead strips to a minimum might be preferred, or on the contrary widening the dead strips to enhance the advantage mentioned above with respect to purity, but the width of the luminescent strips must always remain sufficient.

The invention, of course, may be applied to all color television tubes with one or more guns, comprising a screen formed

by phosphor strips and, near the screen, at least one grid acting in conjunction with the screen as a focusing means. When this grid is a color selection grid with a variable potential, V_g , this should be understood to mean its average potential.

5 With tubes according to the invention, and a test pattern comprising a black and a white portion respectively covering the left and the right half of the screen, contrast values have been obtained, which reached 100 or more (against about 10 for a conventional tube) between two points located at a distance of 3 centimeters from the theoretical line separating the black and white portions, and a contrast of 250 or more (against approximately 20 for a conventional tube) between two points located 10 centimeters from said line.

I claim:

15 1. A color television picture tube of the type comprising: a screen formed by phosphor strips of different colors; a grid facing the screen and adjacent thereto, said grid defining apertures substantially parallel to the strips; means for producing an electron beam directed toward said screen; means for applying to the screen a high positive potential V_E ; means for applying to the grid a potential V_g lower than V_E whereby the grid-screen assembly defines a system of cylindrical lenses convergent for said beam; and the potential V_g being between one-third and three-quarters of the potential V_E .

20 2. The color television picture tube of claim 1, further comprising diaphragm means adapted to prevent lateral portions of the cross section of the electron beam from impinging upon said strips.

25 3. The color television picture tube of claim 2, wherein each grid interval is bounded by two groups of three wires in contact with each other.

30 4. The color television picture tube of claim 3, wherein the axes of the three wires of each of said groups form the edges of a triangular prism.

35 5. The color television picture tube of claim 4, wherein at least two of the three wires of each group have different diameters.
